UNITED STATES PATENT OFFICE.

SEYMOUR MORRISON, OF INDIANAPOLIS, INDIANA.

FOLDED PAPER-BOARD FILLER FOR BOXES.

1,854,413.

Specification of Letters Patent. Patented Sept. 28, 1920.

Application filed December 1, 1919. Serial No. 341,804.

To all whom it may concern:

Be it known that I, SEYMOUR MORRISON, a citizen of the United States, residing at Indianapolis, in the county of Marion and 5 State of Indiana, have invented a new and useful Folded Paper-Board Filler for Boxes, of which the following is the specification.

The object of this invention is to form a 10 filler for instrument-holding boxes out of paper board that will be light, inexpensive, durable, and well-shaped for the purpose.

The manner of cutting, scoring, and folding the paper board is illustrated in the accompanying drawings, in which:

15 Figure 1 is a top plan view of a box, without a cover, furnished with my improved filler.

Fig. 2 is a vertical cross-section of same on the line 2—2 of Fig. 1.

20 Fig. 3 is a view, in the flat, of a paper board, cut and scored, from which a lower base member is folded.

Fig. 4 is a section on the line 4—4 of Fig. 3, of the base member after it is folded.

25 Fig. 5 is a cut and scored paper blank from which a superimposed filler-member is formed.

Fig. 6 is a perspective view of same when 30 nearly folded to form the superimposed filler-member.

Fig. 7 is an end elevation of the two filler-members assembled for use.

Like characters of reference indicate like 35 parts in the several views of the drawings.

Variation in form and proportions will be made to suit the shape and size of the instrument for holding which the filler is to be used, and the number of separate pockets will also vary with the number of instru-

40 ments to be packed in a single box. In the drawings, a filler is shown to hold three instruments and to be used in a box 8. The shape of the instrument requires a deep recess A, extending to the bottom of the

45 box at one end of the latter; a raised table B, as for an instrument with a long thin neck; a recess C of same depth as A but narrower; and a table D on which the major length or body of the instrument is sup-

50 ported. This much, illustrated in detail in Figs. 3 and 4, is formed from a single paper board, in a manner presently to be described in detail; but there is nothing to separate the three instruments from each other and

55 to hold them snugly to prevent breakage,— which is liable if they are made of glass.

Also the body of the filler, if made out of a paper board thin enough to be readily cut and formed into shape, is not sufficiently strong and rigid.

60

I therefore provide a second filler-member illustrated in detail in Figs. 5, 6, and 7, to supplement the first, and to supply the desired additional features.

Describing now the first filler-member, 65

Fig. 3 illustrates the blank cut and scored, ready to be folded to form for use. The width of the blank opposite the table B, is wider than that which is opposite D to provide supporting sides B', and ends B'', of 70

greater width than sides D', and ends D'', D'', to raise table B above table D in the manner shown in Fig. 4. Cuts 1, 2, 3 and 4, 75

form four tongues b, which are folded to positions at right angles to B, so that when 80 ends B'' are bent down to position of support for B, the tongues will make edge-contact against B and reinforce the supporting sides B', as shown by dotted lines in Fig. 3. The

bending lines are appropriately scored as 85 shown by the dotted lines bounding sections B and D and separating sections A and C and tongues b, b, b, b from their adjacent integral sections. The blank is folded to the

form shown in longitudinal section in Fig. 4 85 and in plan and cross-section in Figs. 1 and 2, respectively, the last two figures also showing the manner of assembly in box 8.

The blank for the second filler-member is 90 illustrated in Fig. 5, the body E, of which, is substantially rectangular. This is scored as shown by the transverse dotted lines, for accurate and convenient bending to provide three trough-like recesses each to receive the

body of an instrument to be packed in the 95 box. These recesses are separated from each other, and also from the sides of the box, by relatively thick, hollow, partitions, by the

hollow formation of which a degree of elasticity is afforded to the thin paper-board 100 sides, thereby relieving the contacting instruments from dangerous impact in handling or transportation. The width of each

partition is determined by the distance between the scorings defining the sections F; 105

their height by the scorings defining the supporting sections F'; and distance apart by the width of sections F''. The sections F'' rest upon the surface D, of the first

filler-member. The two outside vertical 110 supporting sections F'', F'', are made enough wider than the intermediate sup-

ports F' , to reach to the bottom of box 8, between the sides of the box and filler sides D^3 , which also reinforces the latter. These sections F^3 , have integral 5 tongues F^4 , of the same width as sections F , which are folded at right angles to F^3 , in the direction shown by the arrow and dotted lines in Fig. 5, and overlap each other across the end of the finished second filler member, and each section F' has a short tongue F^5 , which is bent at right angles away from adjacent section F , and contacts one of the folded tongues F^4 .

The floor spacers F^2 are each continued to 15 form a tongue F^6 , and each of these is scored transversely at its junction with F^2 , by which it is bent up inside of the tongues F^5 , and also for two more bends, one around the upper edges of tongues F^4 , F^5 , and underlapping 20 the corresponding section F^2 . The various steps are illustrated in Fig. 6 where the underlapping is shown by dotted lines. The ends of tops F extend to provide short tongues F^7 which give the end an even 25 finish when assembled in the box.

The assembly together of the two filler members, and their assembly in box 8, is made permanent by gluing together the contacting surfaces, or as many as are necessary 30 to hold the members in folded position, and also to retain them in the box.

It will be understood that the form of my invention here shown and described is by way of illustration only, and that various 35 modifications will be made within the limits of the claims to adapt it to the construction of the instruments to be contained, and what I claim as new and wish to secure by Letters Patent, is:

40 1. The combination, with an instrument case, of a filler formed out of paper board scored and bent at the scores to form a plurality of tables laterally of each other and table supports, and integral reinforcing 45 tongues folded against one or more of said table supports to increase the thickness and strength of the latter.

2. The combination, with an instrument case, of a filler formed out of paper board 50 scored and bent to form a plurality of tables laterally of each other at different heights from the bottom of the case, and table

supports of appropriately varying sizes, and integral reinforcing tongues folded against one or more of said table supports to increase 55 the thickness and strength of the latter.

3. The combination with a box, of a filler formed out of two separate paper boards one of which supports the other and is supplemented and reinforced by it, the supported member also having integral members which bear against the bottom of the case.

4. The combination, with a box, of a filler formed out of a paper board scored and 65 bent to form a plurality of hollow partitions, the blank from which the filler is formed having a plurality of tongues some of which are bent at right angles to the partitions and other of which tongues are bent 70 around said first tongues and secured to the under side of the filler after the first tongues have been bent to final positions.

5. A filler formed out of a paper board 75 scored and bent to form a plurality of hollow partitions, the sides of all of the partitions except the two outermost having integral tongues which are bent toward each other in pairs and the two outermost sides having longer tongues which are overlapped 80 against said first bent tongues, and the integral spacing members between the partitions 85 each having a tongue which is bent around and closely contacted with the adjacent ones of said other tongues.

6. A filler formed out of a paper board 90 scored and bent to form a plurality of hollow partitions, the sides of all of the partitions except the two outermost having integral tongues which are bent toward each 95 other in pairs and the two outermost sides having longer tongues which are overlapped against said first bent tongues, and the integral spacing members between the partitions each having a tongue which is bent around 100 and closely contacted with the adjacent ones of said other tongues and glued to the bottom of the filler, and short tongues from the tops of the partitions to make an even finish.

In witness whereof I have hereunto set my hand at Indianapolis, Indiana, this 17th day of November, 1919.

SEYMOUR MORRISON.
